UNITED STATES PATENT OFFICE

2,439,144

DEVICE FOR SHARPENING DRILLS

John Perkins, London, England

Application November 30, 1944, Serial No. 565,945
In Great Britain June 15, 1944

3 Claims. (Cl. 51—219)

1

This invention relates to the sharpening of small fluted drills.

The main object of the present invention is to provide simple devices for enabling small drills to be sharpened by hand even by unskilled persons.

A further object is to provide a device whereby both cutting edges of a small drill may be sharpened with a single setting-up of the drill in the device.

The invention consists in brief in a small drill-sharpening device comprising a drill holder having drill-locating means and drill-clamping means for holding a drill in fixed position with its end suitably presented simultaneously to a pair of planes inclined to the axis of the drill, said planes comprising means on the holder for guiding a hand-manipulated sharpening stone or the like.

The invention also consists in a drill-sharpening device as set forth in the preceding paragraph, wherein said drill-locating means comprises a V groove or like abutment surface, a spring-urged clamping jaw and a spring-urged plunger preferably mounted on an adjustable carriage, the end of said plunger being adapted to engage a flute in a drill to be sharpened.

The invention also consists in a drill-sharpening device as set forth in either of the two preceding paragraphs, wherein said drill clamping means comprise a clamping jaw and positive means for urging said jaw towards a drill abutment surface.

The invention also consists in a drill-sharpening device as set forth in any of the three preceding paragraphs, wherein said holder comprises an inverted V-shaped block, the intersecting surfaces of which comprise the two intersecting planes referred to.

The invention also consists in a drill-sharpening device as set forth in the preceding paragraph, wherein said surfaces are provided with hard inserts, e. g., of tungsten carbide.

The invention also consists in a drill-sharpening device as set forth in the first of the two preceding paragraphs, wherein rollers are provided let into said surfaces for the purposes described hereinafter.

The invention also consists in a drill-sharpening device as set forth in any of the six preceding paragraphs, wherein means are provided for axially locating a drill prior to sharpening thereof.

The invention also consists in a drill-sharpening device as set forth in the preceding paragraph, wherein said means comprise a rigid arm

2

pivoted on said holder and furnished at its free end with an adjustable screw or the like.

The invention also consists in a drill-sharpening device substantially as hereinafter described with reference to the accompanying drawings.

Referring to the accompanying diagrammatic drawings:

Figure 1 is a vertical longitudinal sectional view of a convenient construction of drill sharpener embodying the present invention.

Figure 2 is an inverted plan view thereof.

Figure 3 is a plan view of part thereof.

Figure 4 is a vertical longitudinal sectional view of part of the device showing a drill in position

15 for sharpening.

Figure 5 is an end view of the device.

Figure 6 is an enlarged plan view of part of the sharpener with a drill in position, and

Figure 7 is an enlarged inverted plan view of the device shown in Figure 6.

In carrying the invention into effect according to one convenient form illustrated by way of example in Figures 1-5, I provide a block of steel *a* which in end view is of polygonal V form, the base of the block being about 1 1/4" in width and about 4" in length. The intersecting V surfaces *b* of the block are mutually inclined at an angle of about 82° and the ridge formed by the intersection of the surfaces stands about 1" above the base *c* of the block. The ends of the block lie in planes at right angles to the ridge and one of these ends *d* is provided with a V groove *e* extending vertically from the ridge to the base of the block, the groove being of sufficient depth to enable any twist drill up to a diameter of, say, 3/32" to rest snugly therein.

A hole is drilled longitudinally through about the centre of the block to accommodate a rod *f* carrying at one end a pivoted jaw *g*, the other end being screw-threaded to receive a knurled knob *h* internally screw-threaded.

The jaw is provided with a V-grooved face so that when the rod *f* is passed through the hole and screwed tight, the groove in the face of the jaw abuts a drill *i* and the jaw holds the drill rigidly in the V groove *e*.

The rod *f* is furnished with a light helical spring *j* serving to urge the jaw lightly towards the V groove *e*.

A pair of locating pins *kk* are fixed to the block to maintain the jaw substantially opposite the groove *e*. This end *d* of the block is also furnished with an annular member *m* the semi-circular extension portion of which is provided with a curved slot *n* radiused approximately about the

centre of the groove *e* and mounted on this extension piece is a carriage *o* having a clamping screw *p* passing through the curved slot *n*.

The carriage embodies a spring-urged plunger *q* set at an angle of about 30° to the horizontal, i. e., to the line of the ridge, the chisel-shaped end *r* of the plunger being sufficiently fine to enable it to bear against the edges of a flute of the smallest drill intended to be sharpened by means of the device.

The angle of the carriage to the plane of the adjacent end of the block may be varied by slackening the clamping screw *p*, moving the carriage and retightening; suitable markings may be placed on the carriage and on the semi-circular extension portion of the member *m* to assist in setting the carriage.

A rigid arm *s* is provided pivoted on the block, the arm being furnished at its free end with a screw *t* and locknut *u* whereby a drill may be set in position with its end resting against the head *v* of the screw *t* and projecting above the V surface planes *bb* to a predetermined extent.

In order to sharpen a twist drill *i* it is passed upwards between the V groove *e* and V clamping jaw *g*, the knurled knob *h* having been loosened and thrust endwise to overcome the light helical spring *j*. The pivoted arm *s* carrying the screw is moved into position over the upper end of the groove *e* and the drill arrested thereby. The end *r* of the spring-urged plunger during this operation is allowed to bear against a flute of the drill by slackening the knurled nut *w*, thus ensuring that the drill is correctly presented to the planes of the intersecting V surfaces. The knurled knob *h* is now tightened, the pivoted arm *s* swung clear and the nut *w* tightened to retract the plunger *q*; finally the flat face of a sharpening stone (not shown) is applied to one V face *b*. The stone may now be moved backwards and forwards by hand in contact with the V face, and in contact with the projecting tip of the drill and when this projecting portion has thus been ground away to the full extent permitted, the sharpening stone is then similarly applied to and operated in conjunction with the other face *b*. The sharpened drill is then removed from the holder by first slackening the knurled knob *h* and then withdrawing the drill downwards.

By this means both cutting faces of the drill are sharpened, the correct backing-off angle lying usually between about 5 and 10° being determined by the pre-set angle of the spring plunger carriage *o*.

The swinging arm *s* for axial location of a drill to be sharpened may be dispensed with if desired. Also, it is not essential to employ two intersecting surfaces but if only one be employed then it is necessary to re-set each drill to be sharpened by rotating it through 180° after one of its cutting faces has been sharpened.

In order to resist wear of the surface or surfaces *b* guiding the sharpening stone, these surfaces may be formed of or provided with inserts of highly resistant material, e. g. case hardened steel or tungsten carbide.

I claim:

- 15 1. A small drill-sharpening device comprising a drill holder having means for laterally locating a drill in relation thereto and drill-clamping means for holding said drill in fixed position with its ends suitably presented simultaneously to a pair of planes inclined to the axis of the drill, said planes comprising surfaces on the holder for guiding a sharpening stone, said device incorporating an adjustable carriage, a spring-urged plunger mounted thereon, the end of said plunger being adapted to engage a flute in said drill and wherein said drill-locating means comprises a V-groove abutment surface on said device.
- 20 2. A drill sharpening device as claimed in claim 1, wherein said holder comprises a solid block of material of polygonal cross-section, two intersecting surfaces of which comprise guiding surfaces for co-action with said sharpening stone.
- 25 3. A drill sharpening device as claimed in claim 1 including an adjustable drill-point-abutment member pivotally mounted on said device for axially locating said drill prior to securing it by said clamping means.

JOHN PERKINS.
